Fig. 2.

Fig. 3.

FIGURE 1 is a perspective view of an airplane embodying my design.

FIGURE 2 is a front elevational view of an airplane embodying my design.

FIGURE 3 is a side elevational view of an airplane embodying my design.

The dominant features of the design reside in the portions shown in full lines in the drawings.

My design for an airplane is characterized by the particular nacelles, shaped as shown, in association with the V-shaped tail fins, all as shown.

I claim:

The ornamental design for an airplane as shown, and described.
